J. G. GILBERT.

Vapor Lamp.

No. 18,142.

Patented Sept. 8, 1857.

UNITED STATES PATENT OFFICE.

JOSEPH G. GILBERT, OF NEW YORK, N. Y.

VAPOR-LAMP.

Specification of Letters Patent No. 18,142, dated September 8, 1857.

To all whom it may concern:

Be it known that I, JOSEPH G. GILBERT, of the city, county, and State of New York, have invented a new and Improved Self-
5 Generating Gas-Lamp; and I do hereby declare that the following is a full and exact description thereof, reference being had to the accompanying drawings and to the letters of reference marked thereon.
10 The nature of my invention consists in surrounding the wick tube with cork and sulfur in such a manner as to prevent the wick tube coming in direct contact with any portion of the lamp, thereby confining the
15 heat to the wick tube through the intervention of the cork and sulfur, both of which are non or poor conductors of heat; also a peculiar formed burner as hereinafter described, which burner screws on or within
20 the wick tube.

To enable others skilled in the art to make and use my invention, I will proceed to describe its construction and operation.

I use a lamp of any of the known forms, 25 see letter A in the accompanying drawings, drill a hole through the top B of said lamp in the center, somewhat larger than the wick tube C, shape a piece of cork into a conical form of such proportions that the
30 base will enter within the screw of lamp top B, from thence tapering to the end or nearly so of the wick tube C, see accompanying drawings, letter D, form a conical shaped cylinder E without its apex of such proportions
35 that the base will be of the same diameter as the screw of lamp top B and of sufficient length to extend to the end of wick tube C, so that when slid over the cork D a space will be left between the cork D and
40 the cylinder E. The wick tube C is passed through the lamp top B, so as to nearly reach the bottom of the lamp when the top B is screwed down in its place. The cork D having been pierced is slid over the wick
45 tube C, the base entering within the screw of top B, the cylinder E is slid over the cork D and the base soldered to the screw of top B. Fused sulfur G is then poured into the space between D and E, which binds
50 the whole compactly.

The heater F'' is made from metal tubing sawed transversely, so as to form two rings equally distant but joined on one side by leaving a portion of the tube unsawed. Under this joining is soldered a cap of sufficient size to screw over the end of wick tube, see letter F, take a gas burner tip H that will admit of or emit a flame of the bat wing or fish tail shape, pass such burner tip H through the cap F and joining (after piercing and cutting a thread in the same and a corresponding one on gas burner tip H, which tip H should be flush with the inside of cap F and project outside between the rings about one quarter inch). The rings 55 are intended to be sufficiently distant apart to receive the heat of the gas jet without the flame coming in contact with them. Introduce a piece of wicking I by means of a wire and the lamp is ready for use. In thus describing its construction I do not wish to confine myself to any particular manner of arranging the cork and sulfur, as they can be made to produce the same results by different devices, such as changing their relative position to the wick tube, or by dispensing with the outer cylinder by dipping the wick tube and cork in the fused sulfur, coating them as thick as desirable, and in many other ways using the combination of 60 the cork and sulfur. Neither do I wish to confine myself to any particular form of gas tip burner in connection with my invention. 70

I do not claim the use of cork alone. Nor 75 do I claim the outer cylinder, as they are both old devices. Neither do I claim the form of the ring separately as a part of the heater or burner.

What I do claim and wish to secure by 80 Letters Patent of the United States is—

The combination of sulfur and cork in the manner and substantially for the purposes set forth.

JOSEPH G. GILBERT.
